UNITED STATES PATENT OFFICE.

ROBERT MORRISON, OF NEWCASTLE, ENGLAND.

IMPROVEMENT IN STEAM-HAMMERS.

Specification forming part of Letters Patent No. 33,595, dated October 29, 1861.

To all whom it may concern:

Be it known that I, ROBERT MORRISON, of the town and county of Newcastle-upon-Tyne, in the Kingdom of Great Britain, have invented a new and useful Improvement in the Hammer-Bar for Steam-Hammers; and I do hereby declare that the following is a full and exact description of the same, reference being had to the accompanying drawings, and to the figures and letters of reference marked thereon.

My invention is an improvement upon the mode of constructing the hammer-bar for such steam-hammers as are described in a patent granted to me in the Kingdom of Great Britain, dated August 6, 1853; and consists in an improved method of guiding the hammer-bar and directing it down upon its work, instead of carrying the framing-standards above the top of the cylinder for the purpose of guiding therein the hammer-bar by means of a cross-head formed on the upper end of the latter. I now provide a simple and effective means of preventing the hammer-bar from turning on its axis, to insure an accurate direction of its blows down upon the work by reducing the entire length of the upper half of the hammer-bar on one side or on both sides to form flat surfaces, or on all sides to form a square or an oval shape, or with a feather or key let into the said bar, or any other section, to prevent it from turning upon its axis, which, fitting to a correspondingly-shaped stuffing-box in the top of the cylinder, acts as an effective guide for the hammer-stroke.

This improvement has reference only to that class of my improved hammers which is intended for general forging work, those employed exclusively for puddling purposes and with round faces requiring no such means of preventing a change in the position of the hammer-face.

In order that my said invention may be fully understood, I will now proceed more particularly to describe its construction and operation.

Referring to the drawings forming part of this specification, in which the same letters of reference allude to similar parts throughout the several views, Figure 1 is a front elevation of my improved steam-hammer, showing one of the modes for preventing the bar from turning upon its axis; Fig. 2, a corresponding ele-

vation of the same at right angles to Fig. 1; Fig. 3, a detached elevation of the hammer-bar; Fig. 4, a plan of the same, corresponding; Fig. 5, a horizontal section of the frame and steam-cylinder, with the hammer-bar in position; Fig. 6, transverse section, showing both sides of the bar flattened; Fig. 7, transverse section, showing all the sides flattened and forming a square.

The steam-cylinder A is bolted between the two frame-pieces B by rows of bolts passing through longitudinal flanges C in the cylinder and corresponding flanges in each frame-piece, the latter being at their bottom expanded ends bolted down to the foundation-plate D, their upper ends being flush with the top level of the cylinder. The working-piston G is forged upon the hammer-bar H at its longitudinal center, and provided with a single packing-ring, confined in a groove turned out of the piston. The lower part, a, of the hammer-bar is round, and extends downward through a deep stuffing-box, F, cast solid with the cylinder to form its lower end cover. The upper half, b, of the hammer-bar, above the piston G, is longitudinally flattened off on one side, in the manner best seen in Fig. 5, and, by being confined in a correspondingly-shaped stuffing-box, I, acts as an accurate guide in directing the hammer-face down upon the work, and the other modes are used in like manner. The hammer-bar, besides being longitudinally guided in its movements in the upper and lower stuffing-boxes, is thus effectually prevented from turning on its axis, so that shoulders, collars, and other projections can be hammered down with certainty to their intended size and form by means of the side of the hammer.

Having thus described the nature of my invention, and the manner in which the same may be used, I desire to be understood that I do not wish to confine myself to any particular shape of the section of the upper half of the hammer-bar, or to any particular number of longitudinal flat surfaces upon the same, any such change in its construction being but an unimportant deviation from the means herein described for accomplishing the same object; but what at present, with respect to the improved construction of steam-hammers patented by me in the Kingdom of Great Brit-

ain, August 6, 1853, No. 1,843, I claim as my invention, and desire to secure by Letters Patent, is—

Flattening off the hammer-bar of such apparatus, working through both ends of the cylinder, or any other section which will prevent the bar from turning upon its axis, substantially as described, whereby, in addition to its being longitudinally guided in the upper and

lower stuffing-boxes, it is effectually prevented from turning on its axis.

ROBT. MORRISON.
